L. C. BAYLES

AUTOMATIC AIR FEED AND ROTATION MOTOR CONTROL FOR ROCK DRILLS

Filed Nov. 12, 1921

INVENTOR
Lewis C. Bayles.
BY
Herbert K. Lyden
HIS ATTORNEY

UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

AUTOMATIC AIR-FEED AND ROTATION-MOTOR CONTROL FOR ROCK DRILLS.

Application filed November 12, 1921. Serial No. 514,648.

To all whom it may concern:

Be it known that I, LEWIS C. BAYLES, a citizen of the United States, and a resident of Easton, county of Northampton, and 5 State of Pennsylvania, have invented a certain Automatic Air-Feed and Rotation-Motor Control for Rock Drills, of which the following is a specification accompanied by drawings.

10 This invention relates to fluid pressure rock drills of the hammer type, but more particularly to means for controlling the feeding element and the rotation element of a stope drill.

15 In my co-pending application, Serial No. 408,299 filed September 4, 1920, I have disclosed a hand operated valve for increasing the rotation and reducing the power of the fluid pressure feed, by supplying fluid pressure from the feeding element to the rotation motor. The object of the present invention is to automatically increase the rotation and reduce the power of the feed by permitting the passage of motive fluid 20 from the feeding element into the rotation motor. For illustrative purposes, I have chosen to show a form of automatic device controlled by the resistance to rotation or 25 torque of the motor, although I do not confine myself to any particular automatic device except as defined by the claims appended hereto.

30 My invention is illustrated in the accompanying drawings, in which—

35 Figure 1 is a side elevation partly in vertical section of a rock drill embodying the invention,

40 Figure 2 is a detail transverse sectional view taken on the line 2—2 of Figure 1 looking in the direction of the arrows,

45 Figure 3 is a transverse sectional view on the line 3—3 of Figure 1, and

Figure 4 is a detail transverse sectional view in diagrammatic form taken through 50 the rotation motor on the line 4—4 of Figure 1.

55 Referring to the drawings, a stope drill is illustrated in the figures, having the cylinder A and front head B provided with the rotation sleeve C through which the drill steel D extends in position to receive the impact blows of the hammer E. An independent fluid actuated rotation motor is provided for rotating the drill steel, having the gears F, only one of which is shown

in Figure 1, in the motor casing, formed by the back end portion G of the cylinder. A head block G' is shown located between the back end portion G of the cylinder and the fluid pressure feed cylinder H having 60 the piston J and piston rod K provided with rock engaging foot L. The cylinder A, back end portion or motor casing G, head block G' and feed cylinder H, are suitably held together by means of the usual through 65 bolts (not shown). One of the gears F of the motor, is operatively connected through a suitable shaft O and pinion P, meshing with the gear Q on the rotation sleeve C, for rotating the drill steel. A sleeve H' 70 is preferably located between the feed cylinder H and the head block G' and a stem or rod R, having a head J' within the head block G', slidably but non-rotatably engages the piston J as by means of a rib H' 75 in the piston and a longitudinal groove K' in the stem or rod R. In accordance with this construction, the head block G' and portions of the machine carried thereby, may rotate relatively to the head J' so 80 that an automatic valve L', to be described, may be mounted within the head block G' and actuated by the torque of the rotation motor, which varies in accordance with resistance to rotation of the drill steel. 85

Fluid pressure, as live air, is supplied to the machine at the inlet S and passes through the admission port T to the percussive element, controlled by the throttle T', having the handle T'', and also through the 90 small port r to the feed cylinder H, around the reduced neck r' of the valve L'. Fluid also passes to the rotation motor through the valve chamber V and admission port W, controlled in this instance by the automatic 95 regulating valve U, covered by United States Patent No. 1,414,168 granted April 25, 1922, to Fred M. Slater and myself. This valve U need not be further described, than to say that it is provided with a tapered head X which controls the admission of fluid pressure to the motor and an increased back pressure from the motor through the port Y on the plunger head Z, assisted by the light spring a, tends to open the valve 100 wider and admit more pressure to the motor as needed. A corresponding reduction of pressure on the plunger head Z permits the tapered head X of the valve to move inward against the light spring pressure and 110

reduce the supply to motor as required. The machine is provided with the usual manually operated rotation handle *b* suitably secured to a portion of the casing as for instance, the head block *G'*.

The head block *G'* is conveniently provided with a valve casing *c* within which the valve *L'* extends and moves longitudinally. A spring *d* held in position by the cap *e*, having the vent *f*, normally urges the valve *L'* inwardly and maintains the passage *g* leading from the valve casing to the valve chamber of the valve *U*, closed, so that the passage of motive fluid from the feed cylinder *H* around the reduced portion *r'* of the valve *L'* and thence through the passage *g* and the passage *Y* to the motor is normally cut off. The inner head *h* of the valve *L'* bears against a shoulder *j* on the non-rotatable head *J'* within the head block *G'*, so that upon a sufficient increase of resistance to rotation of the drill steel to compress the spring *d*, the head block *G'* and drill casing and connected parts will be rotated backwardly or counter-clockwise as Figure 2 is viewed, thus moving the valve *L'* longitudinally in its casing and permitting the passage of motive fluid from the feed cylinder *H* into the rotation motor for increasing the power of rotation when most needed. The action is automatic and independent of the manipulation of the operator.

The port *W* leading to the motor is so restricted that it cannot pass enough air to cause the motor to run away even when the motor is unloaded, therefore in view of the unavoidable leakage existing in this class of motors, the port *W* will not pass enough air to build up a high pressure in passage *Y* and produce high rotating torque in the motor even when the valve *U* is fully open. For this reason the pressure in the passage *Y* is always lower than the pressure in the air feed and when the communication is opened the air will always flow from the air feed through the passage *g* to the passage *Y*.

In addition, the passage *r* is made of restricted area, so that while it is sufficient to maintain pressure in the air feed under normal working conditions, it will not maintain this pressure when air is being drawn down to the motor through the passage *g* and at such times the pressure in the air feed will be reduced, and some air will pass out of the air feed to the motor.

I claim:

1. A rock drill of the hammer type, having a fluid actuated rotation motor and a fluid pressure feeding element, and automatic controlling means for increasing the rotation by opening communication for fluid pressure from the feeding element to the rotation motor.

2. A rock drill of the hammer type, having a fluid actuated rotation motor and a

fluid pressure feeding element, and automatic controlling means for permitting the passage of motive fluid from the feeding element into the rotation motor, to thereby increase the rotation.

70

3. A rock drill of the hammer type, having a fluid actuated rotation motor and a fluid pressure feeding element, and automatic controlling means for increasing the rotation and reducing the power of the fluid pressure feed, by opening communication for fluid pressure from the feeding element to the rotation motor.

75

4. A rock drill of the hammer type, having a fluid actuated rotation motor and a fluid pressure feeding element, and automatic controlling means for increasing the rotation by opening communication for fluid pressure from the feeding element to the rotation motor, and reducing the power of the fluid pressure feed.

80

5. A rock drill of the hammer type, having a fluid actuated rotation motor and a fluid pressure feeding element, and automatic controlling means for reducing the power of the fluid pressure feed, including means for simultaneously increasing the rotation.

85

6. A rock drill of the hammer type, having a fluid actuated rotation motor and a fluid pressure feeding element, and automatic controlling means for reducing the power of the fluid pressure feed, including means for simultaneously increasing the rotation by exhausting the feeding means into the rotation motor.

90

7. A rock drill of the hammer type, having a fluid actuated rotation motor and a fluid pressure feeding element, and automatic controlling means for reducing the power of the fluid pressure feed, and increasing the rotation, by connecting the feeding element to the intake of the rotation motor.

95

8. A rock drill of the hammer type, having a fluid actuated rotation motor and a fluid pressure feeding element, and automatic means controlled by the resistance to rotation for opening communication for fluid pressure from the feeding element to the rotation motor for increasing the rotation.

100

9. A rock drill of the hammer type, having a fluid actuated rotation motor and a fluid pressure feeding element, and automatic means controlled by the resistance to rotation for permitting the passage of motive fluid from the feeding element into the rotation motor, to thereby increase the rotation.

105

10. A rock drill of the hammer type, having a fluid actuated rotation motor and a fluid pressure feeding element, and automatic means controlled by the torque of the motor for opening communication for fluid

115

120

125

pressure from the feeding element to the rotation motor for increasing the rotation.

11. A rock drill of the hammer type, having a fluid actuated rotation motor and a fluid pressure feeding element, and automatic means controlled by the torque of the motor for permitting the passage of motive

fluid from the feeding element into the rotation motor, to thereby increase the rotation.

In testimony whereof I have signed this specification.

LEWIS C. BAYLES.
